UNITED STATES PATENT OFFICE.

JAMES H. HINCHLIFFE, OF MEREDITH, NEW HAMPSHIRE.

STOCKING AND THE ART OF KNITTING THE SAME.

SPECIFICATION forming part of Letters Patent No. 374,408, dated December 6, 1887.

Application filed August 2, 1886. Serial No. 209,774. (Specimens.)

To all whom it may concern:

Be it known that I, JAMES H. HINCHLIFFE, of Meredith, in the county of Belknap and State of New Hampshire, have invented certain new and useful Improvements in Stockings and the Art of Knitting the Same, of which the following is a specification.

My invention relates to stockings and to the art of knitting the same.

10 It is the object of my invention to produce an improved mode of knitting a seamless stocking properly shaped to fit the leg and foot of the wearer.

15 It is also the object of my invention to produce a stocking of improved structural character, which shall be seamless throughout and shaped to fit the leg and foot of the wearer, the foot and ankle portion, or that portion coming within the shoe of the wearer, being knit in plain stitch and the leg portion above the shoe being knit in rib stitch and with a greater number of stitches than is contained in the foot and ankle portion, and without "eyelet-holes" at the junction of the "ribbed" with 25 the plain portion.

To the foregoing ends my invention consists in the stocking and the art of producing the same, hereinafter fully described, so that others skilled in the art may practice and make and 30 use the same, the invention being particularly set forth in the claims hereto appended.

Of the drawings hereto annexed and forming a part of this specification, Figure 1 represents a side elevation of a stocking embodying my invention, the upper portion of the leg being shown in outline merely. Fig. 2 represents an inside or "wrong-side" view of a portion of the fabric comprising my stocking, at the junction of the plain portion constituting 35 the foot and ankle, with the ribbed portion comprising the leg. Fig. 3 represents a diagram, hereinafter referred to, indicating the operation of the needles at certain points in the process of knitting my improved stocking.

40 Figs. 4 and 5 represent a dial and a cylinder-needle and their relative positions, as well, also, as their relation to the fabric and loops produced thereby at one point on the machine when the change is made from plain to rib work, a fraction of a yarn-guide and yarn fed thereby being shown in Fig. 4. Fig. 6 is an exaggerated view of a portion of the fabric at

the junction of the plain with the ribbed fabric, showing the manner of closing the eyelet-holes.

55

Similar letters of reference indicate similar parts in all of the figures.

In carrying out my invention I first knit the toe *a*, foot portion *b*, heel *c*, and ankle portion *d* in plain stitch on any circular-knitting machine capable of knitting what is commonly known as "bulge" toe and heel, employing, for example, a machine like that shown and described in Letters Patent of the United States to James L. Branson, No. 149,192, dated March 31, 1874, and commencing at the toe, as is commonly done in knitting stockings with a bulge toe and heel on machines of the type mentioned. The knitting is continued in plain stitch above the heel until an ankle portion of sufficient length is produced, preferably to a point just on a line with the top of the boot or shoe, say at the point indicated by the letter *e* in Figs. 1 and 2. I now transfer the web to a circular machine adapted to knit 70 ribbed work, and employing as many cylinder-needles as were employed in the cylinder upon which the foot and ankle portion of my stocking were produced and as many dial-needles in addition. The machine shown in 80 the patent to George E. Nye, of Bristol, Pennsylvania, No. 316,907, dated August 28, 1885, may serve to illustrate the mode of procedure at and from this point forward.

The machine disclosed in the patent last before mentioned is shown as equipped with two yarn-guides and two needle-operating cams at different points in the circumference of the cylinder. These two points may be supposed to be located with respect to each other, as indicated by the letters *w* *r* in Fig. 3. In addition to moving the dial-cams to control the operations of the dial-needles, I construct the cams to move the cylinder-needles so as to operate the same in like manner, as is common 95 in circular machines of this and other types, and as is well understood by all knitting artisans who have had any experience in producing stockings or webs on circular machines employing reciprocating needles. After transferring the web to the cylinder-needles of said latter machine, I so adjust the needle-operating cams at the point *r* that the cylinder-needles will be moved to produce plain knit-

ting as before, while the dial-needles will be held entirely out of action, and so that if at the point *w* both the dial and cylinder needles were held out of action a tubular web in plain 5 stitch might be produced, as on the "Branson" machine, before mentioned. At the point *w*, however, I feed in an additional yarn or thread, *e*, and so adjust the cams for moving the dial-needles *f* that the latter will be operated to 10 their full extent, but regulate the cams for moving the cylinder-needles *g*, so that the latter will be raised high enough only to take the yarn or thread *e*, but not to carry the loop *h* in their hooks below the latches *i*, as shown 15 in Fig. 4, the result of which will be, when the needles are retracted, to leave two loops in the hooks of the cylinder-needles and one in the hooks of the dial-needles, as represented in Fig. 5. When, now, the point *r* is reached, 20 at which point, as stated, the dial-needles are out of operation, the cylinder-needles will take the regular yarn or thread, each cylinder-needle drawing it through the two loops held by it, leaving but a single loop in the hooks 25 of the needles, as before. If knitting should be proceeded with in this manner, the result would be a web having a right side of substantially the same nature as before, with ribs on the "wrong" side attached to the portion 30 of the main thread intermediate of the loops formed thereby, as will be understood by reference to Fig. 6 of the drawings. Knitting in this way is continued preferably for two rounds or courses, when the thread or yarn *e* 35 is severed, and both the dial and cylinder needles at the point *w* are thrown out of action and the dial-needles at the point *r* brought into operation in conjunction with the cylinder-needles, the result of which will be regular 40 one-and-one-ribbed work with twice the number of stitches in the tube produced as in the plain-stitch work of the foot and ankle portion, in which way the knitting of the stocking is proceeded with to the top *j*, 45 when, if desired, the additional thread *e* may be brought into use with the dial and cylinder needles at the point *w*, as before, for the purpose of securing the stitches at the top of the stocking from readily running or raveling 50 back while the article is being manipulated for the purpose of hemming or otherwise finishing the top.

The result of beginning ribbed work on a fabric knit in plain stitch in the manner set 55 forth will be that the extra thread or yarn *e* will be so formed in loops on the part of the yarn between or joining the wales of the plain-knit fabric as to effectually close what would otherwise be eyelet-holes at the points where 60 the dial-needles begin the formation of stitches.

In Fig. 6 I have shown, on an exaggerated scale, the structural character of the fabric at the point of junction of the plain with the ribbed portion, as well, also, as the relationship of the supplemental thread *e* and the loops formed therefrom to the main thread *e'* and its loops. In this view, A represents the

loops formed by the cylinder-needles; B, the loops formed by the dial-needles when first thrown into operation so as to catch the main 70 thread *e'*, and C the eyelet-holes that would ordinarily be formed at the junction of the plain with the ribbed web. The full dark lines indicate the loops formed by the dial-needles from the supplemental thread *e* attached to the main web, as shown, said loops being made on the back or wrong side, between the wales of the plain-knit portion, on a line with the subsequently-formed wales or ribs knit by the dial-needles in the ribbed portion, and, as a consequence, over the eyelet-holes C, as shown. The last loops formed by the dial-needles from the supplemental thread will be looped with the first loops B, formed 75 by the dial-needles from the main thread *e'*. 80 85

A stocking constructed in the manner set forth will have that part thereof coming within the boot or shoe of no more than ordinary thickness, so as not to interfere with the wearing of a boot such as may be worn with stockings of common construction, while the part of the stocking above the boot, designed to protect the limb of the wearer against cold, will be substantially of double thickness, and be at the same time larger or fuller, so as to 95 fit the calf or enlarged part of the limb. It may also be mentioned that the appearance of the stocking on the out or "right" side is substantially the same in both the ribbed and plain portions, so that no objection arises on 100 that score.

As stated, the extra thread *e*, knit in at the junction of the ribbed with the plain portion, is formed in loops on the back of the yarn connecting each two wales of the plain-knit 105 portion at the points where eyelet-holes would occur if additional needles were simply brought into operation to produce ribbed work without employing such additional thread in the manner explained. 110

Having thus described my invention, I claim—

1. A stocking having the foot and ankle portion, or that portion designed to come within the boot or shoe of the wearer, knit in plain stitch, and the leg portion above the ankle knit in rib stitch, with a considerably greater number of stitches in the rib or leg portion than in the foot and ankle or plain-knit portion, an extra yarn or thread being 120 looped on the back of the portion of the yarn connecting each two wales of the plain-knit portion in the course just preceding or adjacent to the first rib course and looped or joined to the latter course, as set forth. 125

2. The improvement in the art of knitting stockings, which consists in knitting the toe, foot, heel, and ankle portions in any known way, looping an extra yarn or thread on the back of the portion of the yarn or thread connecting each two wales of the plain-knit portion, then adding an additional number of stitches, as rib stitches, between the stitches comprising the plain-knit portion, and form-

ing the leg portion of the stocking in rib stitch, substantially as hereinbefore set forth.

3. The improvement in the art of knitting on two sets of needles, with two yarn-guides and two sets of needle-operating cams, which consists in first knitting a web on one set of needles with one yarn-guide and one set of needle-operating cams in operation, and then knitting with said set of needles, yarn-guide, and 10 needle-operating cams at one point, and with the same set of needles and the other set of needles and other yarn-guide and set of needle-operating cams at another point, the first-mentioned set of needles at the latter point 15 being operated so as not to cast the loops upon them, but to take the yarn from the latter yarn-guide, as set forth.

4. The improvement in the art of beginning the knitting of rib work on plain-knit work 20 in the process of knitting a stocking, which

consists in forming plain-knit work from a main thread on one set of needles, then bringing into operation a second set of needles, and forming loops or stitches thereon from a supplemental thread, connecting such loops with 25 the main thread of the plain-knit portion, and finally knitting on both sets of needles with the main thread, discontinuing knitting with the supplemental thread, and looping the last loops formed by the second set of needles from 30 the supplemental thread with the first row of loops formed by both sets of needles from the main thread alone, as set forth.

In testimony whereof I have signed my name to this specification, in the presence of two sub- 35 scribing witnesses, this 16th day of July, 1886.

JAMES H. HINCHLIFFE.
